KNEE KICKER

Filed Dec. 31, 1929

Fig. 1.

Fig. 0.2.

A technical line drawing of a dental instrument, possibly a periodontal probe or a similar dental tool. The instrument has a long, thin, tapered tip (1) that curves downwards and to the right. The handle (2) is cylindrical and tapers towards the tip. Numbered callouts point to various parts: 3 points to a rib or ledge on the handle; 4 points to a small circular feature on the handle; 5 points to the junction where the handle meets the tip; 6 points to the tip itself; 7 points to a rib or ledge on the handle; 8 points to a rib or ledge on the tip; 9 points to a rib or ledge on the tip; 10 points to a rib or ledge on the tip; 11 points to a rib or ledge on the tip; 12 points to a rib or ledge on the tip; 13 points to a rib or ledge on the tip; 14 points to a rib or ledge on the tip; 15 points to a rib or ledge on the tip; 16 points to a rib or ledge on the tip; 17 points to a rib or ledge on the tip; 18 points to a rib or ledge on the tip; 19 points to a rib or ledge on the tip; 20 points to a rib or ledge on the tip. The drawing is signed 'Fig. 3.' in the bottom right corner.

UNITED STATES PATENT OFFICE

ELBA V. HOOBLER, OF WATERVILLE, OHIO

KNEE KICKER

Application filed December 31, 1929. Serial No. 417,783.

This invention relates to an improvement in knee kickers, especially designed for stretching carpet while it is being laid and secured in place.

The object of my invention is to greatly improve and simplify the construction and use of such a stretching implement, and one of the improved features lies in the construction of the teeth or prongs which are allowed to penetrate the carpet to only a predetermined extent, thereby holding the carpet while preventing the prongs from scratching or marring the floor.

This makes it unnecessary to provide for regulating or adjusting devices for the teeth, and the extent of penetration thereof.

Another improved feature lies in the construction of the handle or head which is made good and strong and yet is a soft pad to be bumped with the knee of the user in stretching the carpet.

In the accompanying drawing:

Fig. 1 is a perspective view showing the application of the implement;

Fig. 2 is a sectional view through the pad; and

Fig. 3 is a similar view through the opposite end of the implement.

The implement is provided with a handle 1 having a block 2 attached to one end thereof, and glued or otherwise secured to this block is a pad 3 preferably of soft sponge rubber and of approximately the shape of the block 2, covering the outer side thereof.

A strip of leather 4 or other similar material, such as fabric or the like, is secured over the pad 3 and is held in place by a metallic band 5.

At the opposite end of the handle 1 is a metallic head 6 having a socket 7 receiving the end of the handle 1 for securely attaching the head thereto. A plate 8 is secured beneath the head 6 by set screws 9, or other form of attaching means, and a lip 10 is formed on the outer edge of the plate 8 to prevent relative forward movement of the head.

Teeth or prongs 11 are fixed in the plate 8 and extend downwardly and forwardly therefrom, as shown in Fig. 3, at an angle

to the plane of the plate. These teeth or prongs are provided with penetrating points 12 on the lower ends thereof, between which and the body portions of the prongs or teeth are shoulders 13. These shoulders limit the extent to which the prongs may penetrate the carpet or other material and prevent the prongs or teeth from extending through the carpet and causing injury or a marring of the floors, as so often happens where the extent of penetration is not limited.

By the provision of such shoulders, no adjusting means is required for otherwise regulating the extent of penetration, thus simplifying the construction and making it impossible for the degree of penetration to change or vary.

As is well known, this stretching implement is used in stretching the edges of the carpet by placing the head over the carpet with the prongs penetrating the same, and by bumping against the pad with the knee or limb of the person using the same, the carpet is stretched and may be secured in its proper position.

I claim:

A stretching implement of the character described comprising a light metallic head, a facing plate having a solid portion with perforations extending thereinto from the under side, a plurality of prongs or teeth fixed in the perforations, said prongs or teeth comprising pins of equal length and being of approximately uniform diameter throughout a major portion of their length and having a reduced point for engaging and holding a carpet or the like, and a shoulder formed on each tooth or prong at the junction of the reduced point with the uniform major portion for regulating the extent of penetration into the carpet, the inner ends of the pins abutting the head and being secured in the solid portion with said shoulders equally spaced downwardly from said solid portion.

ELBA V. HOOBLER.
